UNITED STATES PATENT OFFICE.

GEORGE JAY ANDERSON, OF WEST SUPERIOR, WISCONSIN.

HOISTING-MACHINE.

SPECIFICATION forming part of Letters Patent No. 397,621, dated February 12, 1889.

Application filed May 8, 1888. Serial No. 273,180. (No model.)

To all whom it may concern:

Be it known that I, GEORGE JAY ANDERSON, of West Superior, in the county of Douglas and State of Wisconsin, have invented a new and Improved Hoisting-Machine, of which the following is a full, clear, and exact description.

The object of the invention is to provide a new and improved hoisting-machine, specially adapted for loading and unloading vessels, cars, &c.

The invention consists of certain parts and details and combinations of the same, as will be described hereinafter, and then pointed out in the claims.

Reference is to be had to the accompanying drawings, forming a part of this specification, in which similar letters of reference indicate corresponding parts in all the figures.

Figure 1 is a side elevation of the improvement with parts broken out. Fig. 2 is an end elevation of the same. Fig. 3 is an enlarged end elevation of part of the improvement. Fig. 4 is an enlarged sectional side elevation of the carrier and tripping device; and Fig. 5 is a plan view of the carrier.

The improved hoisting-machine is provided with a mast consisting principally of a vertical frame, B, provided on its bottom with a pin, B', mounted to turn in a bearing, C', formed on the platform C. On the upper end of the frame B, in its middle, is held a pin, B², mounted to turn in a suitable bearing formed in the ends of the beams D' of a suitable frame, D, erected on the platform C, next to the upright frame B.

From the bottom of the frame B project outward and upward the beams B³, which, in connection with the beams B⁴, secured to the top of the frame B, support the boom E, made of two parallel beams, E' and E², connected at the top and bottom by cross-pieces E³, said beams E' and E² thereby forming a track on which travels the carrier or carriage F, provided with the usual wheels, F', supporting a frame, F², in the middle of which is mounted to rotate a pulley, F³, over which passes the hoisting-rope G, secured by one end to a transverse bar, F⁴, held on the frame F² of the carrier F.

The beams B³ are united at their outer ends,

which are connected by a link, B⁵, with the pin B², and from the said ends of the beams B³ extend the braces B⁶, supporting the lower part of the boom E. From the upper part of the frame B extend the braces B⁷, which assist in supporting the upper part of the said boom E, which is thus held on the mast in such a manner that the weight concentrates in the lower part of the frame B, and the latter is thereby easily turned on its pivots—the pins B' and B².

The hoisting-rope G supports the hoisting-bucket H by passing under a pulley, H', mounted to rotate in a frame, H², carrying at its lower end a hook, H³, supporting a bail, H⁴, pivotally connected at its ends to the sides of the bucket H⁵, said bucket H⁵ being limited in its swinging movement by the stops H⁶ and H⁷, against which said bail H⁴ rests alternately, the stops H⁶ and H⁷ being secured to the outer portions of the sides of the bucket H', as is plainly shown in Figs. 1 and 4.

On the middle part of the bail H is hinged an inclined rod, H⁸, provided on its outer end with a notch, H⁹, adapted to engage a projection, H¹⁰, secured on the rear wall of the bucket H⁵. Said rod H⁸, when engaging said projection H¹⁰, holds the bucket H⁵ in a vertical position, so that the bucket supports the load to be carried. Said rod H⁸ is to be disengaged from the projection H¹⁰ by a tripping device, I, consisting principally of a U-shaped lever, I', fulcrumed at I² to the outer sides of the beams E' and E² of the boom E, as illustrated in Figs. 1 and 4. The lever I' is provided at each end with an upwardly-extending projection, I³, connected with one end of a spring, I⁴, secured by its other end to the side of the respective beam E' or E². The outer end of the said projection I³ is also pivotally connected by a link, I⁵, with a block, I⁶, held to slide on top of the respective beams E' and E² of the boom E, the said blocks I⁶ being connected with each other by a cross-piece, I⁷, and the said blocks are adapted to be engaged by the wheels F' of the carrier F in order to operate the tripping device I. The hoisting-rope G also passes over a pulley, J, mounted to rotate in a block, J', pivotally connected with the upper end of the boom E. The rope then passes from this pulley J to

a sheave, J^3 , supported from a transverse beam, D^2 , of the frame D . The hoisting-rope G then extends downward and is connected with a windlass, K , of any approved construction, and located on the platform C . One end of the block J' carrying the pulley J is connected with one end of a rope, L , extending rearward and passing over a sheave, L' , supported on a post of the frame D , and the said

10 rope L then extends downward and is secured by its lower end to a cleat, L^2 , secured to the lower end of the said post of the frame D .

To the front axle of the carrier F is connected one end of a rope, N , extending upward and passing between pins J^2 , held in the block J' , and then passing on farther upward and over a pulley, N' , mounted on a transverse beam, D^3 , of the frame D , and then the said rope extends along the said beam D^3 and 20 passes over a pulley, N^2 , and then under a pulley, N^3 , supporting a weight, N^4 , and then the said rope N extends upward and is secured by its end to a cleat or pin, N^5 , secured on the said beam D^3 .

25 In the frame D is formed a hopper, O , provided on its lower end with a spout or chute, O' , which is adapted to be connected with cars or other receptacles to be loaded. On the front end of the hopper O is pivoted a transverse extension-plate, O^2 , adapted to 30 close the upper front end of the said hopper whenever desired.

The operation is as follows: The platform C usually forms part of a dock, and on the 35 said platform is mounted to swing the mast, so that the lower end of the boom E can be brought over a vessel to be unloaded. The mast, with its boom E , is turned on the pivots B' and B^2 by pulling on the rope L or G 40 until the lower end of the boom E is in the desired position, so that the hoisting-bucket H is directly over the hatch of the vessel to be loaded. The rope L is then fastened by its lower end on the cleat L^2 , and then the 45 windlass K is operated, so as to unwind the hoisting-rope G , whereby the carrier F by its own weight travels downward on the beam E until the hoisting-bucket H is directly over the hatch of the vessel. This downward 50 movement of the carriage F causes a downward movement of the rope N , and when the desired position of the said hoisting-bucket over the hatch is reached then the operator fastens the end of the rope N to the pin or cleat 55 N^5 in such a manner that the pulley N^3 is in its uppermost position—that is, between the pin N^5 and the pulley N^2 . The rope N will now prevent a further downward movement of a carrier F at all times, and when the operator now continues to unwind the rope G from the hoisting apparatus K the said rope G will cause the bucket H to pass down the hatch into the hold of the vessel. The bucket is then loaded in the usual manner and the 60 rod H^8 holds it in a vertical position by engaging by its notch H^9 the projection H^{10} . When the bucket is filled, the hoisting appa-

ratus K is again set in motion, so as to wind up the rope G , whereby the hoisting-bucket H is lifted out of the hold through the hatch

70

until the pulley H' comes in contact with the pulley F^3 of the carrier F . A further winding up of the rope G now causes an upward traveling movement of the carrier F with the hoisting-bucket H . On the upward movement

75

of the carrier F its front wheels, F' , come in contact with the blocks I^6 , which are then moved forward and cause an upward swinging movement of the lower part of the lever I' by being connected with the latter by the

80

links I^5 . The middle part of the **U**-shaped lever I' is thus thrown against the bottom edge of the rod H , so that the latter is swung upward and out of contact with the projection H^{10} . The bucket, on account of being heavier at its front end than at its rear, tilts over, turning at the pivot-points the lower end of the bail H^4 .

85

As the bucket H^5 at this time is directly over the hopper O , the contents of the bucket H^5 are thrown into the said hopper O , after which the bucket H^5 rights itself and the

90

notch H^9 of the rod H^8 again engages the projection H^{10} . When the bucket is loaded, its forward or inclined half is the heavier, and therefore as soon as the latch is released the

95

bucket dumps; but when empty the rear half of the bucket is the heavier, and hence the bucket will right itself, as stated, as soon as dumped. When the carrier F travels upward, as before

100

described, the weight N^4 causes the pulley N^3 to exert a pressure on the rope N , so that all slack of the latter is constantly taken up. Now, the operator again causes the hoisting apparatus K to unwind the hoisting-rope G , and the carrier F , with the hoisting-bucket H , travels downward until the pulley N^3 , carrying the weight N^4 , is again in its uppermost position, as before described, and the said carrier F is then held in a fixed position directly over the hatch of the vessel to be unloaded.

105

When the carrier F moves downward from its uppermost position, the springs I^4 move the lever I' and the blocks I^6 back to their former positions, so as to be ready to engage the rod H^8 again, as before described. Thus it will be

110

seen that the entire machine is easily operated and the boom can be swung to any desired position and held there, so that the hoisting-bucket is always over the hatch of the vessel and connects at its upper end with the

115

hopper O , the latter being sufficiently wide to permit the bucket H to unload when in an angular position, as shown in dotted lines in

120

Fig. 2. It will further be seen that the entire device is very simple and durable in construction and very effective in operation.

125

Having thus described my invention, what I claim as new, and desire to secure by Letters Patent, is—

130

1. The combination, with the frame D , having a hopper, O , of the vertical mast journaled in said frame in front of the hopper, and hav-

ing an inclined boom, E, extending rearwardly beyond the mast into the frame over the hopper, and a carriage traveling on the boom past the mast, substantially as set forth.

5. 2. The combination, with the supporting-frame, and the vertical mast adapted to rotate and having an inclined track-boom extending in rear of the mast at its upper end, and provided with a trip at said rear end, of a carriage traveling on the boom and carrying a dumping-bucket provided with a latch into the path of which said trip projects, substantially as set forth.

10. 3. The combination, with the frame having forwardly-projecting top beams, D', and a forwardly-projecting base, C, of the vertical mast journaled in the said projecting parts of the beams and base, and having an inclined boom projecting at its rear or upper end beyond the 15 mast, the carriage traveling on the boom, the rope N, passing over pulleys on the frame secured at its ends to the frame and having a weighted pulley, N³, suspended from it, the

hoisting-rope G, secured to the carriage and having a traveling pulley, H', under the carriage, passing thence over a pulley on the carriage to a pulley on the frame, and the rope L, for turning the boom, substantially as set forth. 25

4. The combination, with the inclined boom and the carriage traveling thereon, of the tripping-lever I, pivoted at the upper end of the boom projecting forwardly thereunder, provided at its ends with upwardly-extending projections I², springs I⁴, connected to the boom and said projections, links I⁵, extending rearwardly from said projections, and the blocks I⁶, sliding on the boom in the path of the carriage and connected to said projection, whereby when the carriage forces the blocks rearwardly the lever I' will be operated, substantially as set forth. 30 35 40
